(57) CLAIM

The ornamental design for an animal leash for multiple pets, as shown and described.

DESCRIPTION

FIG. 1 is a top plan view of an animal leash for multiple pets, showing my new design;

FIG. 2 is a top plan view of the animal leash for multiple pets of FIG. 1 shown in a condition of use; and,

FIG. 3 is a left side elevation view of the animal leash for multiple pets.

In FIG. 2, the broken lines showing animals depict environmental subject matter and form no part of the claim.

1 Claim, 3 Drawing Sheets

FIG. 3
